X-RAY CONTROL CABINET

Edward B. Graves, South Euclid, Ohio, assignor to Picker X-Ray Corporation, Waite Manufacturing Division, Inc., Cleveland, Ohio, a corporation of Ohio

Application October 25, 1949, Serial No. 5,697

Term of patent 14 years

(Cl. D26—5)

To all whom it may concern:

Be it known that I, Edward B. Graves, a citizen of the United States, residing at South Euclid, county of Cuyahoga, and State of Ohio, have invented a new, original, and ornamental Design for an X-Ray Control Cabinet, of which the following is a specification, reference being had to the accompanying drawings, forming a part hereof:

Fig. 1 is a front elevational view of an X-ray control cabinet showing my new design; Fig. 2 is a top plan view of the cabinet; Fig. 3 is an elevational view of the right hand side of the cabinet, the left hand side being the same, and Fig. 4 is a fragmentary rear elevational view thereof.

I claim:

The ornamental design for an X-ray control cabinet, as shown and described.

EDWARD B. GRAVES.
